Bradford Webster INVENTOR

BY

Poplham & Webster ATTORNEYS

UNITED STATES PATENT OFFICE.

BRADFORD WEBSTER, OF LOUISVILLE, KENTUCKY, ASSIGNOR TO WEBSTER LOOSE-LEAF FILING COMPANY, A CORPORATION OF KENTUCKY, BANKRUPT; FERD R. MOELLER, TRUSTEE IN BANKRUPTCY.

BOOK.

1,233,827.

Specification of Letters Patent.

Patented July 17, 1917.

Application filed August 23, 1909, Serial No. 514,253. Renewed February 28, 1916. Serial No. 81,062.

To all whom it may concern:

Be it known that I, BRADFORD WEBSTER, a citizen of the United States, residing at Louisville, in the county of Jefferson and 5 State of Kentucky, have invented a new and useful Book, of which the following is a specification.

My invention relates to books or filing devices, in which leaves and other loosely attached elements are bound on posts or guides; and the object of my invention is to provide a simpler, more durable, and more efficient structure in the binder and in the attachments. 10
15 The invention consists of novel features and parts and combinations of the same, which will be more fully described herein-after and then pointed out in the claims. A practical embodiment of the invention 20 is represented in the accompanying drawings which are part hereof and in which similar characters of reference indicate the corresponding parts in all the views.

Figure 1 is a longitudinal elevation of the book laid flat; Fig. 2, an enlarged sectional view of the lockable post engaged by the locking slide; Fig. 3, a plan of the lockable post; Fig. 4, an elevation of the lockable post; Fig. 5, an end elevation of the binder 25 with covers attached; Fig. 6, a perspective view of the locking slide; Fig. 7, a perspective view of the loosely attachable binding spring and Fig. 8 shows the upper portion 30 of a free post with a fragmentary sectional view of the casing bar and slide.

My invention consists of a lower base, in which are set preferably a plurality of lockable posts; of an upper casing bar, containing a locking slide, and having set therein a plurality of free pins or posts; of top and bottom covers connected respectively to said bases; of loosely attachable sheets; and of 40 loosely attachable binding springs.

The lower base comprises a stiff bar X in 45 which are set the lockable posts C and C' and a label-holding device W, preferably perpendicular to said base and integral therewith. The label-holding device W is preferably provided with bent edges on two opposite sides to contain a card.

The lockable posts C and C' are perforated near their locking ends for the admission of the penetrating elements of the slide K and K'.

The casing bar A is preferably U-shaped 55 in cross-section, the inclosed side being toward the outside of the book and being adapted to assist in guiding the locking slide D in its longitudinal movement. The free pins or posts B and B' are set firmly in both 60 opposite faces of the casing bar A. The inner face of the casing bar A is provided with openings adapted to admit the lockable posts C and C' and to hold them against any 65 transverse movement. The outer face of the casing bar A is also provided with corresponding openings adapted to admit the lockable posts C and C' and to coöperate with the openings in the inner face to hold them against any transverse movement. As 70 shown in Fig. 1, the pins or posts B and B' are of such length as to stop the casing bar A and the locking mechanism D in exact position lengthwise of the posts so that the perforating members will find the perforations in the lockable posts accurately. 75

The slide D is slotted to receive the pin or post B', the edges of which opening control the longitudinal movement of the slide. One of the inside edges of this slot is provided 80 with a resilient projection M, adapted to engage the post B' resiliently and to prevent free movement of the slide. This prevents the slide from jarring loose and thus unlocking the book.

The slide D is provided with upwardly and downwardly bent pieces L at the end to form a convenient grip for the thumb and forefinger. 85

The slide D is slotted to receive and hold 90 in position the lockable posts C and C'. In the ends of these slots are set the penetrating pieces K and K', preferably pointed and integral with the slide D. These pieces K and K' are recessed so that when the posts 95 C and C' are pulled down into the slide as shown in Fig. 2, the slide D is locked firmly against any sliding motion.

The loosely attachable binding spring E is provided with a flat bearing surface, with a 100 single long slot to admit the two lockable posts C and C' and with a leaf-spring at each end formed by bending each end of the bar inwardly. These leaf-springs extend beyond the free posts B and B' and are slotted 105 to admit said posts. The flat bearing surface is provided with openings for containing closely the posts B and B'. The slots

in the leaf-springs cooperate with the posts B and B' to prevent the spring from rocking.

I do not limit myself to the exact form in which my invention is herein disclosed, further than is indicated in the claims which follow:

1. In a loose-leaf book, file, and the like, in combination, a post-locking slide, supporting elements on opposite sides thereof, and an element connecting said supporting elements; said slide being provided with means for creating a resilient engagement between itself and said connecting element.
15. 2. In a loose-leaf book, file, and the like, in combination, a pair of bases and one or more leaf-retaining members set in each; the leaf-retaining members of one base being perforated; the other base comprising means for penetrating and locking said perforated leaf-retaining members and a supporting element therefor adapted to admit said perforated posts to the locking position.

3. In a loose-leaf book, file and the like, in combination, a perforated leaf-retaining member, a supporting member, means associated with said supporting member for penetrating and locking said perforated leaf-retaining member, and leaf-retaining means associated with said supporting member for throwing said perforated member into a locking position.

4. In a loose-leaf book, file, and the like, provided with retaining members, a loosely attachable binding spring, comprising a bearing surface and inwardly extending leaf springs from each end thereof; said bearing surface and said leaf springs being perforated to admit a retaining member through each leaf spring and a portion of the bearing surface thereunder.

BRADFORD WEBSTER.
